UNITED STATES PATENT OFFICE.

ALBERT CZARNYSZKA, OF MILWAUKEE, WISCONSIN.

SHADE AND CURTAIN FIXTURE.

Application filed June 10, 1921. Serial No. 476,401.

To all whom it may concern:

Be it known that I, ALBERT CZARNYSZKA, a citizen of the United States, residing at Milwaukee, county of Milwaukee, and State 5 of Wisconsin, have invented new and useful Improvements in Shade and Curtain Fixtures, of which the following is a specification.

This invention relates to combination 10 shade and curtain fixtures.

It is the object of this invention to provide an ornamental fixture which may be clamped to a window frame to support both shades and curtains without marring 15 the wood work by using screws to secure the fixture.

It is a further object of this invention to provide a fixture adapted for use in the aforesaid manner upon two window frames 20 angularly inclined to each other as in a bay window construction, the device being adjustable to adapt it for the various angular positions in which it may be used.

In the drawings:

Figure 1 is a view, partially in elevation and partially in perspective, of that part of the device intended for use in the angle of a bay window.

Figure 2 is a front elevation of that form 30 of the device which is adapted to engage a single window frame member.

Figure 3 is an elevation of one end of the device shown in Figure 2.

Figure 4 is an elevation of the other end 35 of the same.

Figure 5 is a front elevation of a form of the device which is applicable to a double window frame such as is found where two windows are located side by side.

Figure 6 is a horizontal section thru the window casings of a bay window showing, in plan, the device illustrated in Figure 1 and a device similar to that shown in Figures 2 to 4 inclusive.

Figure 7 is a cross section thru a pair of window casings disposed side by side showing, in plan, those forms of the device shown in Figures 2 to 5 inclusive.

Like parts are identified by the same reference characters thruout the several views.

It will be understood that for use upon a single window frame or upon the outside frame members of a series of adjacent frames, it will be necessary to use the single form of this device as it is illustrated in Figures 1, 3, 4, 6 and 7. The device shown

in Figures 2, 3 and 4 is identical with that shown at the right hand side of Figure 7. At the left hand side of Figure 6 there appears a device similar in all respects to that shown at the right hand end of Figure 7 with the exception that the parts are reversed to adapt the device for application to a left hand frame member instead of to a right hand frame member. Such a reversal of the parts is easily understood and is well known in the art and therefore, only one of these devices—that shown in Figures 2, 3 and 4—will be described.

The body of the device, shown in Figures 2, 3 and 4, consists of a base plate 10 to the outer face of which strips 11, 12 and 13 may be secured to form a pair of longitudinal dove-tail grooves 14 and 15. A piece of fiber or other non-metallic material 16 70 may be glued to the back of the base plate 10 to prevent abrasion of the woodwork thereby.

Attached to the strips 11 and 12, or otherwise secured to base plate 10, is the upwardly projecting post 18. Carried by this post are the two arms 19 and 20 which have a slight inclination upward from the horizontal. The arms 19 and 20 are adapted to support curtain rods of a flattened tubular form as shown in Figures 6 and 7. Provision has been made for supporting two curtain rods so that both curtains and over-curtains or lambrequins may be used if desired.

In the dove-tail groove 15 is a correspondingly shaped slide 21, the inner end of which is bent at right angles (Figure 3) to form the arm 22. This arm is made adjustable in length by the provision of a 95 sliding member 23 secured to the arm by means of screws 24 which slide in slot 25 therein. At 26 the inner end of the sliding member 23 is bent inwardly at right angles (Figure 7) to frame engaging position.

Fastened upon the slide 21 is the horizontally projecting post 30 which is provided with a threaded aperture adapted to receive screw 31. This screw is provided with a polygonal head 32 by which it may be operated. Spaced a slight distance from the head is a collar 33. An arm 34, similar to arm 22, is confined between the collar 33 and the head 32 of the screw. An extension member 35 is adjustably secured to arm 34 110 by means of screws 36. At its extreme end the extension member 35 is bent at right

angles and sharpened to a chisel point 37 which is adapted to be engaged behind the window casing.

It will be obvious that by turning the head 32 of screw 31, the arms 34 and 22 will be drawn together to engagement of that portion of the window frame lying there between. By means of the adjustment of the extension members 35 and 23 upon said arms, 10 the base plate may be brought to bear upon the outer face of the window casing member 9.

A small block 38 is mounted upon the arm 22 of slide 21. This block is slotted at 15 39 to receive and engage the flattened end member 40 of a shade roller 41 (see the extreme right hand end of Figure 6).

It will be noted that with the bracket clamped in position in the manner hitherto 20 described, the block 38 will be mounted within the window opening. This block is provided for the convenience of those persons who prefer to mount their shades wholly inside of the opening in the window 25 casing.

By way of provision for the mounting of shades exterior to the opening in the window casing, a second slide 45 is operable in the dove-tail groove 10. A set screw 46 30 holds the slide 45 in any desired longitudinal adjustment. Carried by said slide is a horizontally protruding post 47 which carries a block 48, similar to the block 38, upon arm 22. The block 48 is slotted at 49 to receive 35 and engage a shade roller as shown at the right hand side of Figure 7. By adjusting the slide 45, various lengths of shade rollers may be accommodated.

The form of the device illustrated in Figure 5 and at the left hand side of Figure 7 is adapted for use upon two adjacent window casings in the same plane. It is substantially the double of the device shown in Figures 2 and 4. The base plate is of greater length than the corresponding portion of the single form of the device. It carries two upwardly projecting members 18, each of which bears the outwardly extending arms 19 and 20. In the upper grooves 14 are two slides 45, each of which carries a post 47 and roller supporting blocks 48 and 48'. The groove 15 is also provided with two slides 21, each of which carries all of the members appurtenant to slide 21 of Figure 2. The block 30', however, is provided with a left hand thread and so likewise is the screw portion 31'. The screw 31 and the screw 31' have a common head 32' which is held in fixed relationship to the base plate 10 by means of a pair of posts 29 supported from said plate. It will be noted that whereas block 48 is slotted, as is the corresponding block in Figure 2, block 48' is apertured to receive the opposite end of the shade roller. Likewise, the block 38 upon

arm 21 is slotted, whereas block 38' upon the arm 21 at the right hand side of Figure 5 is merely apertured.

Referring now to that form of the device shown in Figures 1 and 6 and adapted for use in the angle between two frames of a bay window, it will be noted that this device is an ingenious combination of two of the single fixture members, as described, so hinged together and adjustable in angle as 75 to permit of clamping the assembled structure to two adjacent angularly disposed window frames.

Two base plate members 10' and 10'' are hinged together by a pintle 8. Carried by the pintle 8 at opposite ends thereof, are the two legs 50 of a U-shaped bridge member 51. Connecting the plates 10' and 10'' are three links 52, 53 and 54 constituting a toggle jointed lever. A screw 55 is made fast to the middle link 53 and is inserted thru a suitable opening in the bridge piece 51. The thumb nut, threaded upon screw 55, bears upon the bridge member 51 and may be turned up upon the screw to actuate the 90 top lever to lessen the angle between plate members 10' and 10''. A suitable lock nut 57, shown in Figure 6, serves to secure the adjustment attained by wing-nut 56.

The plates 10' and 10'' are provided with 95 an upper groove 14 and a lower groove 15 corresponding in function to the similarly designated grooves in the other views. The upwardly projecting members 18 upon each of the base plates carry the curtain engaging 100 rods 19 and 20.

A post 29 is fixed to each of the base plates 10' and 10''. The screws 31 turn freely in these posts and are threaded into the blocks 30 in slide members 21. Each of the slides 21 105 is provided with the arm 22 at right angles thereto and the adjustable end portion 23 carried thereby. The arm 22 at the left end of the device has a slotted block 38 mounted thereon, whereas the arm 22 at the right 110 hand side of the device has a block 38' provided with a hole.

The manner of attachment of this device is obvious. The toggle lever composed of 115 links 52, 53 and 54 is operated by means of screws 55 and thumb nuts 56 to adjust the plates 10' and 10'' to the desired angle. The heads 32 of the two screws 31 are now operated separately to adjust the slides 21 to a clamping position.

As shown in Figures 6 and 7, the several members embodying this invention are adapted to be used in combination as required to bring about any desired result in shade roller and curtain rod mounting upon 125 any conceivable window frame structure.

I claim:

1. A window shade fixture including a pair of hinged plates adapted to rest against adjacent angularly disposed surfaces, means 130

for adjusting said plates angularly to conform to surfaces in a plurality of angular relations, hook-shaped devices at the end of the plates, disposed at right angles thereto and adapted to engage about portions of a window frame, clamping means associated with each of said plates, and curtain and shade roller brackets carried by each of the plates.

10 2. A window shade fixture including a pair of plates angularly adjustable to lie in planes disposed at various angles, means for clamping said plates to adjacent angularly disposed window casings, and means adjustable upon each plate for supporting one end of a shade roller.

20 3. A window shade fixture including a pair of hinged plates, a toggle jointed lever connecting said plates, a screw whereby said lever is operable to vary the angular adjustment of the plates, and a clamping member adjustable relative to the free end of each plate and independently of said screw and lever.

25 4. In a window shade fixture, the combination with a pair of plates in angularly adjustable relation, of slide elements longitudinally adjustable with reference to each of said plates and clamping members adjustably connected with each of said slides and adapted for movement transversely with respect to the path of movement of said slides.

30 5. In a window shade fixture, the combination with a plate provided with inclined arms adapted to support a curtain rod, of a set of slides movable longitudinally of said plate, a clamping arm of adjustable

length carried by one of said slides, a screw adapted to effect the movement of this slide, 40 a shade roller support carried by another of said slides, and means for locking said last mentioned slide in any desired adjustment.

6. In a window shade fixture, a base plate, a slide movable longitudinally of said plate, 45 a screw adapted to control the movement of the slide, a clamping arm of adjustable length carried by said slide, a shade roller support mounted on said arm, an upwardly projecting post attached to the base plate 50 and inclined forwardly therefrom to a point in advance of said screw, and a pair of parallel arms projecting forwardly from said post and adapted to engage and support curtain rods. 55

7. In a window shade fixture, the combination with a base plate, of a pair of slides movably mounted on said base plate, an adjusting bolt carried by said slides and adapted for moving the slides relatively of 60 each other, and a pair of clamping arms, each carried by one of said slides and adapted for adjustment, whereby to adjust said arms for engagement about a portion of a window frame. 65

8. In a window shade fixture, the combination with a pair of members relatively adjustable for spaced relation, of a pair of clamping elements each connected with one of said members for independent adjustment thereon whereby said elements may be engaged with portions of window frames at differing relative distances from their respective members. 70

ALBERT CZARNYSZKA.
